PRINTING MACHINE

Frederick L. Fuller, deceased, late of West Orange, N. J., by Schuyler B. Harrison, East Orange, N. J., and John G. Phillips, New York, N. Y., executors, assignors to International Business Machines Corporation, New York, N. Y., a corporation of New York

Application November 2, 1943, Serial No. 508,676

14 Claims.

(Cl. 101—93)

1

This invention relates to printing mechanisms and more particularly to the type coordinated with manually controlled sorting machines which enables the provision of separate printed lists of the amounts of the checks segregated in the sorting compartments.

Such forms of machine have heretofore been devised as exemplified in the patents to F. L. Fuller, No. 1,966,623, dated July 17, 1934, and to F. L. Fuller et al., No. 2,142,352, dated January 3, 1939.

The main object of the present invention is to improve the printing mechanism shown in the aforementioned patents, particularly with the purpose of effecting a simplification in construction, ease of servicing of the parts and rendering more accessible the printing mechanisms for the ease of detachment of the printed tapes, inserting new paper rolls, placing a new inking ribbon in the printing mechanism, etc.

A further object of the present invention is to devise a construction of printing mechanism which can be assembled at each side of the sorting machine, which construction not only possesses the above named virtues but further makes the machine more attractive from a commercial viewpoint by reason of the fact that the machine may be placed against a wall. In this respect, the present machine overcomes the drawback and objections to the machine shown in the patent to F. L. Fuller et al., No. 2,142,352 in which it will be observed that the separate tape or strip printing mechanisms are mounted at the rear of the machine requiring additional overall floor space.

A further object of the present invention is to provide a printing mechanism which is capable of printing upon a plurality of selected record tapes in which most of the heavy parts of the printing mechanisms are carried by the stationary framework and only a few parts relatively light in weight are required to move. In this respect, the present machine is a major improvement over the construction shown in the patent to F. L. Fuller, No. 1,966,623, which construction has the drawback in that practically all parts of the separate tape printing mechanisms are carried by the rotatable sorting drum. This has been found to greatly increase the load on the motive power of the machine.

A more specific object of the present invention is to provide two separate tape printing mechanisms; one at each side of the machine and each substantially duplicate in construction and operation.

More specifically it is an object of the present invention to provide each printer at each side of the machine with a set of amount printing wheels which are differentially rotated and radially positioned to be coordinated with a selected record

2

strip and to effect printing impressions from the printing wheels upon the selected record tape in a novel manner.

A still further object of the invention is to enable the concurrent radial positioning of the two groups of printing wheels as the sorting drum is rotated back and forth to predetermined check receiving positions and to provide an improved arrangement whereby the group of printing wheels at one side of the machine will be coordinated with the related platens of the separate printing mechanisms when certain compartments are selected for operation and vice versa to coordinate the group of printing wheels at the other side of the machine with the related printing platens when remaining sorting compartments are selected.

To attain the above object, the relative positioning of the group of printing wheels is such that one group of printing wheels is in a midway position with respect to associated platens when the other group of printing wheels is coordinated with associated platens. This midway position of one group of printing wheels is maintained during the time that the other group of printing wheels is associated with the platens for printing upon the selected record tapes and, in a reverse manner, a midway position of the other group of printing wheels is maintained during the time that the remaining group of printing wheels is associated with other platens to effect printing impressions upon the selected record tapes. Hence, by virtue of this principle of operation, only one group of printing wheels is operable at a time for effecting printing impressions on the selected record tape.

Further improvements in the machine consist of adjuncts which are in the form of aligning mechanisms, means for effecting printing impressions by the group of printing wheels by a hammer blow so as to make clear line imprints and other additional improvements which are incorporated in the printing mechanism so that the latter will operate in an efficient manner.

While the present improvements in the printing mechanisms have been coordinated with a manually controlled sorting machine, it is very obvious that the present improvements may be applied to other forms of printing machines such as accounting machines, bookkeeping machines, etc. It is to be understood that the present embodiment is merely illustrative and is set forth to disclose what is considered as the preferred embodiment of the invention and the specific illustration here should not be considered as restrictive.

Other objects of the invention will be pointed out in the following description and claims and illustrated in the accompanying drawings, which disclose, by way of example, the principle of the

invention and the best mode, which has been contemplated, of applying that principle.

In said drawings:

Fig. 1 is a perspective view of the combined check sorting-accounting machine to which the present improvements in printing mechanisms are preferably incorporated.

Fig. 2 shows the control tape printing mechanism of the combined check sorting and accounting machine and also shows the connections made in the present machine to the printing wheel setting segments herein for setting the two groups of printing wheels.

Fig. 3 is a chart provided to diagrammatically show the different relative position of the two groups of printing wheels and the manner in which the relative positioning is maintained as different compartments are selected so that only one group of printing wheels will be effective to print, although both groups of printing wheels are concurrently positioned.

Fig. 4 is a detail view showing the manner of effecting the differential adjustment of the setting segments for the groups of printing wheels and also showing the relationship of a group of printing wheels with several of the printing platens.

Fig. 5 is a view in elevation taken at the rear end of the machine, showing the cross connecting jack shafts and the manner in which they have connections for setting the two sets of setting segments for the two groups of printing wheels.

Fig. 12 is a detail view showing the operating parts involved for operating the aligning mechanism for the group of printing wheels.

Fig. 13 is a detail view showing the operating parts involved to operate the line spacing mechanism for the selected tape printer.

General operation of the machine

The present improvements are preferably applied to the form of combined check sorting and accounting machine shown in the U. S. Patents No. 1,966,623, issued to F. L. Fuller, dated July 17, 1934, and No. 2,142,352, issued to F. L. Fuller and S. Brand, dated January 3, 1939.

The present machine is to be considered as an improvement in the combined check sorting and accounting machine shown in the above patents, particularly in the construction and operation of the tape printing mechanisms associated with the sorting compartments. In order to better understand the present improvements there will be

given a general description of the construction of the combined sorting and printing machine.

The assembled sorting and accounting machine is shown in Fig. 1 and represents except for the tape printing mechanism shown herein the form of machine which is now used commercially in banks to simultaneously list and sort a group of promiscuously arranged checks. The operator is provided with a series of checks 45 which have different classifications and in accordance with their classifications one of the compartment selecting keys 48 is depressed. Through a control mechanism fully shown in the patent to F. L. Fuller et al., No. 2,142,352, a drum is rotated so as to bring a selected sorting compartment into registration with an aperture 46 in which the check to be sorted is manually inserted. The function of the machine in the aforementioned patents is to effect the entries of the amounts on the checks selectively in a plurality of totalizers and to cause the listing of amounts on the checks upon a control tape 49 and also upon separate record tapes which are associated with a plurality of sorting compartments. To provide for the entry and listing of the amounts the machine is provided with an ten key keyboard 429, the keys of which are initially depressed so as to control the setting on suitable setup mechanism of amounts equal in value to the keys struck. After sorting compartment has been selected and the amount has been set up on the setup mechanism, the operator having inserted the check in the aperture 46 then depresses a motor release bar 47. A number of functions are then performed, one of which is the feeding of the inserted check into the selected compartment and also the positioning of totalizer actuators in order that amounts may be entered into the grand totalizer and selectively into one of a plurality of totalizers which are associated with the sorting compartments and furthermore one of a plurality of printing mechanisms associated with the sorting compartments will be selected for operation to print the amount on the selected compartment tape. A printing mechanism shown in Fig. 2 is concomitantly adjusted so as to print the same amount printed on the selected compartment tape on the control tape 49.

The machine is provided with twenty-four compartment totalizers which correspond in number to the number of sorting compartments and separate tape printing mechanisms.

In the prior construction of the separate tape printing mechanisms, as exemplified in the patent to F. L. Fuller No. 1,966,623, they were in their entirety carried by the sorting drum and the item printing wheels were fixed relatively to the tape assemblies. By the differential rotation of the sorting drum the selected tape was associated with the printing wheels and the item printing wheels were impressed against the tape to print the items set up by the keys. In this construction the attachment of the tape assemblies to the sorting drum added considerable weight to the sorting drum, bringing about difficulties in the starting and stopping of the drum, due to momentum and inertia.

This advantage was overcome by the subsequent construction shown in the patent to F. L. Fuller et al. No. 2,142,352 and in this arrangement the tape printing mechanisms were completely divorced from the sorting drum and were fixedly mounted at the rear of the machine. This lessened the weight of the sorting drum and made it still easier to rotate the latter and stop the same

at selected positions but the tape printing mechanisms were complicated in construction and relatively expensive to manufacture.

A further disadvantage was that to remove the separately printed tapes it was necessary for the operator to get access to the rear of the machine. This prevented the mounting of the check sorting and accounting machine directly against a wall, increasing the floor space necessary for the proper operation of the machine and which, in some installations, was found to be objectionable. The advantage of the tape printing mechanism in Patent No. 1,966,623 is that easy access could be had to the printed tapes from one side of the machine and in the present machine this same advantage is gained but, however, avoiding the disadvantages inherent in the patented construction. The present construction is, therefore, considered to strike a favorable medium between the construction shown in the aforementioned patents and consists of a design which is relatively simple to manufacture and service and provides a number of advantages which are attractive from a commercial viewpoint.

The combined check sorting accounting machine shown herein is provided with differentially positionable actuators or slides 635 (Fig. 2) which correspond to those shown in Patent No. 2,142,352 and similarly designated. These actuators are differentially positioned according to the item keys depressed and carry rack segments 637 for actuating the selected totalizer and also carry type elements 636 of the main or control tape printing mechanism for printing on control tape 49. For the separate tape printing mechanisms shown in the patented machine there are connections shown in Fig. 26 of this patent. The present machine also includes the same form of actuating mechanism for slides 635 but a different form of mechanical connection is made from the actuators or slides 635 for setting the printing wheels of the separate tape printing mechanism of the present machine. These connections are shown particularly in Figs. 2 and 4.

Each slide 635 of the present machine is provided with a notch 50 receiving a roller 51 on one arm 52 of a bell crank 53 which is loosely mounted on a support rod 54. Of course, for the ten amount setting slides 635 of the patented machine and the present machine there are ten bell cranks 53, each having a similar connection to the related slide. Each bell crank 53 is also provided with an integral rearwardly extending arm 55 and from the rear of the machine as shown in Fig. 5 it will be seen that the arms 55 are grouped together and are disposed as shown in this figure somewhat to the left of the center of the machine. From these arms 55 there are operating connections to adjust the two sets of actuators for the two sets of printing wheels for the separate tape printing mechanisms. These connections consist in part of a group of five transversely extending shafts 56 mounted above the arms 55 and a group of five transversely extending shafts 57 mounted below the arms 55. These shafts are known as "jack" shafts for the purpose of extending motion from one point of the machine to another point. The arms 55 for the units, hundreds, tens of thousands, millions, hundreds of millions denominations are connected by links 58 to arms 59 secured to the lower jack shafts 57, whereas the arms 55 for the tens, thousands, hundreds of thousands, tens of millions and billions denomination are connected through intermediate links 61 (Fig. 4) to arms 60 secured

to the shafts 56. Therefore, it will be observed that the jack shafts 56 and 57 have been assigned denominational values which are indicated in Fig. 5. To the shafts 56, for example, arms 62 are connected and each of such arms has a link connection 63 (Fig. 4) to an integral arm 64 of the related setting segment 65. For the group of shafts 56 there is at the right end of Fig. 5 a group of arms 62 and these have link connections 63 to the segments 65 for the printing mechanism at one side of the machine and the shafts 57 have similar arms 66 which have link connections 67 to the other segments 65 for the printing mechanism at the same side of the machine. It is also to be understood that the shafts 56, 57 at the left end have similar operating connections from these shafts to the related segments 65 for the printing mechanism at the other side of the machine.

Through the connecting means just described, it is evident that a pair of segments 65 for the same denomination will be adjusted commensurately and in accordance with the differential position of the related slide 635. By the plurality of connections shown in Fig. 5, it is further evident that the two groups of segments 65 are correspondingly positioned for each operation of the machine and such position causes the corresponding positioning of the two groups of printing wheels.

Aligning mechanism for bell cranks 53

It is preferable to provide the slot 50 (Fig. 4) somewhat larger than the diameter of the roller 51 to enable a free positioning of the slides 635 and their independent alignment. To this end, it is desirable to provide an aligning mechanism for the group of bell cranks 53. Each bell crank 53 as shown in Figs. 4 and 6 is provided with a depending segment arm 70 equipped at the bottom with aligning notches 71. Underlying the segments 70 is an aligning bail consisting of side arms 72 and a cross bail 73 which bail is loosely mounted upon a shaft 74. A rock shaft 75 carries arms 76 having link connections 77 to each arm 72 of the bail.

The reference numeral 94 (Fig. 6) designates a cyclically operating main drive shaft of the machine, being the correspondingly designated shaft in Patent No. 2,142,352. From this main drive shaft the various mechanisms of the machine are driven in a timed relation. The means for driving the shaft 94 is fully shown in the last mentioned patent and its rotation is initiated upon depression of the manual bar 47 (Fig. 1) which, when depressed, effects a cyclic operation of the accounting machine. In the present machine shaft 94 carries a box cam 80. Cooperating with the cam race of the box cam 80 is a follower bell crank 84 pivoted on a rod 82. The bell crank 84 has a link connection 83 to an arm 84 loose on a shaft 85. The upper curved portion of the arm 84 has a link connection 86 to an arm 87 loose on the rock shaft 75. An arm 88 secured to the rock shaft 75 has a spring connection 89 to the arm 87.

At substantially 180° rotation of the cam 80 and after segments 65 have been positioned, the bell crank 84 will be rocked counterclockwise, shifting link 83 to the right, rocking arm 84 counterclockwise and shifting link 86 to the right to rock the arm 87. Through the interconnected spring 89 the arm 88 and therefore the shaft 75 to which it is connected is rocked counterclockwise. Rocking the shaft will, through the arms

76, elevate the links 77 and the bail 73. In the differential positions of the bell cranks 53 they will now be positively aligned. It is, of course, obvious that this operation of the aligning mechanism occurs to concurrently align both sets of setting segments 65.

Separate tape printing mechanisms

As previously intimated the present machine includes a novel construction of printing mechanism to provide separate listings of the checks sorted in each sorting compartment and upon the associated tape there is printed the amount of the check sorted in the related sorting compartment. The simplification of the manufacture of the present mechanism is provided by having two duplicate printing arrangements, PL and PR; one at each side of the machine and each to the rear thereof as shown in Fig. 1. The operating connections from the differentially positioned slides 635 to the two sets of segments 65 for the two printing mechanisms have previously been described. Since the printing mechanisms are duplicate in construction the description will be confined to one, particularly for the arrangement shown at the right side of the machine and shown in Figs. 4, 8 and 9.

The printing mechanism in its entirety is supported by two parallel side plates 95 and 96 and attached to the frame plate 95 by mounting screws 97 is a plurality of platen carrying castings 98 spaced from each other. At the bottom of each casting 98 there is inserted a transverse block of impression taking material, such as a block of rubber 99 (Fig. 4). The printing wheels 109 are radially adjusted for an operative correlation with the desired platen 99 to print upon the selected tape, and the series of printing wheels 109 are impressed against the platen by a percussive action to print on the paper tape 100 passing around each platen 99. The support for the paper tape 100 and its movement in step by step increments to space the printed lines will be subsequently explained.

Supported by the side frame plates 95 and 96 is a rotatable shaft 101 (Fig. 9) and loosely mounted upon the shaft 101 are the series of ten setting segments 65. Two side frames 102 and 103 are secured to the rotatable shaft 101 and to provide a rigid framework for the printer the side frame plates 102 and 103 are interconnected by a casting 104 (Fig. 4) which not only gives rigidity to the frame but also provides for the simultaneous positioning movement of the plates 102 and 103 and provides a framework which carries certain parts of the printing mechanism. One of such parts consists of a rod 105 journaled between the plates 102 and 103 and said rod carries a plurality of pairs of pinions 106 and 107, there being one pair 106 and 107 for each of the ten segments 65. The smaller pinion 106 is in continuous meshing relationship with the segment 65 whereas the related larger pinion 107 attached to the smaller pinion meshes with a pinion 108 to which is secured an associated printing wheel 109. The pinion 108 is in mesh with the larger pinion 107 while the segments 65 are being differentially positioned, thereby causing the differential rotation of the printing wheels 109 in whatever position the printing frame 102-103 happens to be in. Each printing wheel 109 is provided with ten digit type 0-9 inclusive but at the normal position of each printing wheel 109 there is no printing type coordinated with the printing platen 99. Therefore, if the print-

ing wheel 109 is not rotated at all, no printing will be effected in the related column of the tape. The omission of printing is effected by cutting away the tooth which would normally carry a type and having this relationship at the normal position of the printing wheel 109. However, any differential rotation of the printing wheel 109 will bring a selected type to print, it being observed that for printing the "0" digit type a rotation of the printing wheel of one step is effected as is fully described in the aforementioned patents.

The rotation of the printing wheels 109 is determined in the machine now being described by the depression of the ten digit keys 420 shown in Fig. 1. Thereafter, a cyclic operation of the machine is effected by depression of the manual bar 47 which cycles the machine to differentially position the segments 65 and correspondingly rotate the printing wheels 109. However, prior to the cyclic operation of the machine there is a radial positioning of the frame 102-103 commensurate with the rotation of the sorting drum so as to bring the related printing wheels 109 in coordination with the selected tape 100 to be printed on. The positioning of the sorting drum is determined by the plurality of compartment selecting keys 48 shown in Fig. 1 and upon depression of one of these keys the rotation of the drum is initiated and effected to a predetermined extent and by an arrangement to be subsequently described the frames 102-103 of both printing mechanisms are concurrently adjusted but only one set of printing wheels 109 of one printing mechanism is coordinated with the tape 100 to be printed upon.

Assuming that the frame 102-103 is in the position shown in Fig. 4 and that the tape 100 just to the left should be printed upon in the next operation of the machine, it is to be understood that the spacing between the adjacent platens 99 are such that with the segments 65 stationary and at normal position and therefore with the blank spaces of the printing wheels 109 coordinated with the platen 99, the positioning of the printing frame 102-103 concurrent with the rotation of the sorting drum will cause the printing wheels 109 to be driven by the pinions 107 as the pinions 106 roll over the now stationary segments 65. The spacing of the platens 99 is such that the group of printing wheels 109 will make one complete revolution when the frame 102-103 moves from one platen to the next as the sorting drum is positioned to select an adjacent compartment. After the frame 102-103 has been positioned under control of the differentially rotated sorting drum, the printing wheels 109 are then differentially rotated and by means to be subsequently described will be impressed against the platen 99 to print upon the selected tape 100.

The sorting mechanism shown in the aforementioned patents consists of twenty-four sorting compartments and since there is one tape printing mechanism for each sorting compartment it is obvious that for each side of the machine there are twelve tape printing mechanisms, as shown in Fig. 8. Since a duplicate arrangement is provided for the other side the machine provides for selective printing upon twenty-four tapes. There will now be described the connections from the sorting drum in the machine shown in the aforementioned patents to the present wheel carrying frames so that the manner in which the printing wheels 109 of only one

printer are positioned to print upon one selected tape 100 at a time will be better understood.

Means for radially positioning the two sets of printing wheels 109

The two frames 102 and 103 at each side of the machine are concurrently positioned by the shaft 114 (Fig. 10) which corresponds to the shaft designated 60 of the machine shown in the Fuller et al. Patent No. 2,142,352. The sorting drum shown in this patent is secured to the shaft 60 and is rotated under control of the compartment selecting keys 48 in either of the two directions to select a compartment to receive a check. Shaft 114 similarly in the present machine is adapted to be rotated clockwise or counterclockwise commensurate with the movement given to the sorting drum. The two printer frames 102—103 are radially positioned by the arrangement shown in Fig. 10 wherein it will be noted that secured to the shaft 114 is a box cam 115 having a cam race 116 which receives a roller 117 of a pitman 118. The lower end of the pitman has a forked portion 119 received by the shaft 114 whereas the upper portion has rack teeth 119 meshing with a pinion 120. It will be noted that the underside of the pitman 118 rests against a roller 121. The pinion 120 is secured to the shaft 54 and the other end of the shaft 54 carries a larger pinion 122 in mesh with a gear 123 secured to the shaft 124. An adjustable coupling 125 (Fig. 9) of any conventional construction is interposed between the shaft 124 and the shaft 101.

By the above operating connection between the sorting drum carrying shaft 114 and the shaft 101 the printer carrying frame 102—103 at the right side of the machine will cause an angular or radial position of this frame according to the compartment selected. It should also be observed that while not shown shaft 124 also extends to the left side of the machine and has a similar connection to the shaft 101 for the positionable printer frame at the left side of the machine. Hence, the position of the printer frame 102—103 at the left side of the machine is also effected by the position of the cam 115 and according to the compartment selected. There will be now explained by reference to the diagram shown in Fig. 3 the manner in which the group of printing wheels 109 at the right side of the machine will be positioned to print upon the selected tape when compartments 1-12 are selected for receiving the check, and in which the group of printing wheels 109 at the left side of the machine will be positioned to print upon the selected tape when compartments 13-24 are selected. This, in general is due to the particular configuration of the cam race 116 of the box cam 115 and the relative position of the two printer frames by means of which one group of wheels 109 always has a midway position with respect to its platens.

The combined check sorting and accounting machine to which the present improvements are applied has provision for sorting papers or checks into twenty-four sorting compartments and these are referred to herein as 1 to 24 and are selected under control of the twenty-four compartment selecting keys 48 shown in Fig. 1. Obviously, since the sorting drum is fixed to the shaft 114, the movement of the sorting drum from one sorting compartment position to the adjacent compartment position will cause an angular movement of the sorting drum, and therefore, the shaft 114 on which the drum is secured, to an extent of 15°. The different positions that the cam 115

takes by the position of the sorting drum for selection of compartments are designated in Fig. 10 and the chart shown in Fig. 3 should also be referred to to understand the present arrangement for selectively printing on the twenty-four printing tapes. It will also be recalled that at the right side of the machine provision is made for printing upon twelve printing tapes Nos. 1 to 12, inclusive, and as the sorting drum moves from the sorting compartment positions 1 to 12, the group of printing wheels 109 for the printer at the right side of the machine are coordinated in succession with the selected platens numbered 1 to 12, inclusive. This is effected during the clockwise rotation of the cam 115 to the positions Nos. 1-12. With the printer frame 102, 103 for the right side of the machine in the position shown in Fig. 8 it will be obvious that the related group of printing wheels 109 are in position to effect printing upon the tape surrounding platen No. 1. This relation of the print wheels and platen No. 1 is shown in the chart in Fig. 3. At this time, sorting compartment No. 1 is in the check receiving position and cam 115 is in the No. 1 position shown in Fig. 10.

However, with regard to the relative arrangement of the printing wheels 109 and the platen No. 24 for the printer at the left side of the machine, it should be observed by the provision of the adjustable coupling such as 125 between the drive shaft 124 and the shaft 101 for positioning the printer 102, 103 for the left side of the machine, the group of printing wheels 109 for this side is set to be midway between platens numbered 24 and 23 as diagrammatically shown in Fig. 3. While the construction for the left side of the machine has not been shown in the drawings this relative positioning can be clearly visualized by assuming that for this left side of the machine the printing wheels 109 are between platens corresponding to platens 1 and 2 for the right side of the machine. The adjustable coupling 125 therefore enables the midway positioning of the printing wheels 109 for the left side of the machine whereas the group of printing wheels for the right side of the machine are in operative correlation with the platens Nos. 1-12 when compartments 1-12 are selected.

Assuming that the operator should desire to select compartment number 2 for receiving a check to be sorted, the related compartment selecting key No. 2 will be depressed to effect a clockwise rotation of the sorting drum and at the same time the shaft 114 and therefore the cam 115 rotates counterclockwise 15° from No. 1 position to No. 2 position. The portion of the cam race 116 for this 15° movement of cam 115 will coat with the roller 117 and through the positioning mechanism shown in Fig. 10 will rotate shaft 124 to now cause the printing wheels 109 at the right side of the machine to be coordinated with platen No. 2. However, since the group of printing wheels 109 at the left side of the machine is still one-half step ahead they will be midway between platens Nos. 23 and 22. In the machine now being described, the sorting drum remains in the last adjusted position and if sorting compartment No. 6 should then be selected, the drum will be rotated to the No. "6" compartment position and cam 115 will cause the further counterclockwise positioning of the printer frame 102, 103 at the right side of the machine to coordinate the printing wheels 109 for this side with platen No. 6 and this will bring the printing wheels for the left side of the

machine between platens Nos. 19 and 18, as shown in the diagram of Fig. 3.

Summarizing therefore, by the selection of any of the compartments Nos. 1 to 12, inclusive, the group of printing wheels 109 at the right side of the machine will always be coordinated with the platens Nos. 1-12 to print upon the associated printing tape. Concurrently with such positioning, due to the half step ahead positioning of the print wheels 109 for the left side of the machine, such wheels will always occupy an intermediate and one-half step position ahead with respect to the associated platens Nos. 13-24. Assuming now that the sorting drum is in the position for selection of No. 12 compartment to receive a check, it is evident that the group of printing wheels 109 at the right side of the machine will be coordinated with platen No. 12 whereas the group of printing wheels 109 for the left side of the machine will be a half step beyond platen No. 13, which has the same relative position as No. 12 platen. If the operator desires to select the compartment No. 13, a 15° movement of cam 115 will ensue but the cam formation for this angular movement of the cam 115 from No. 12 to No. 13 (Fig. 10) is such that only a half step of movement of the printing frames at the right and the left sides of the machine takes place and such movement will be reverse or clockwise as viewed in Fig. 8, for both sides of the machine. This half step of movement of the printing wheels 109 for the right side of the machine will now position the printing wheels 109 between the No. 11 and No. 12 platens whereas the group of printing wheels 109 for the left side of the machine will now be coordinated with platen No. 13 (see Fig. 3) and hence the latter wheels will effect printing upon the tape surrounding platen No. 13. For further clockwise positioning of the cam 115, each successive angular step of movement of cam 115 for 15° will move the printing wheels for both sides of the machine a single step, and for the left side of the machine the wheels 109 will always be coordinated with a platen, whereas, for the right side of the machine the group of printing wheels 109 will maintain their midway positions with respect to the associated platens. The chart shown in Fig. 3 shows diagrammatically the coordination of the printing wheels for the left side of the machine for platen No. 24 whereas the group of printing wheels for the right side of the machine has moved a half step clockwise away from platen No. 1. When the sorting drum moves from compartment No. 24 to compartment No. 1 this again effects only a half step of movement of the group of printing wheels 109 for both sides of the machine to coordinate printing wheels 109 for the right side of the machine with platen No. 1 and to bring the printing wheels for the left side of the machine midway of platens Nos. 24 and 23.

The possibility of causing the printing wheels at the right side of the machine to be coordinated with platens Nos. 1 to 12 during the Nos. 1-12 positions of the cam 115 and to cause the print wheels 109 at the left side of the machine to be coordinated with platens Nos. 13 to 24, inclusive, during the Nos. 13-24 positions of cam 115 results from the relative positions of the two frames and from the construction of the cam race 116. The cam contour of cam 115 makes it possible to offset the two printer frames 102, 103 for the right and left sides of the machine so that the group of printing wheels 109 at the

right side of the machine will be beneath any platen Nos. 1 to 12, inclusive when sorting compartments 1 to 12, inclusive are selected. Further, the printer frame 102, 103 at the left side of the machine will be positioned so that the related group of printing wheels 109 will be coordinated with platens Nos. 13 to 24 when sorting compartments Nos. 13 to 24 are selected for receiving the sorted checks or papers.

It has been assumed in the preceding description that cam 115 is only rotated clockwise but this is because of the description for the selection of compartments 1 to 24 in the order named. However, this may not be the actual operation of the machine because the checks which are to be sorted occur promiscuously with regard to their numbered classifications. The machine shown in the aforementioned patents and herein enables the sorting drum to be rotated directly from one position to the other either counter-clockwise or clockwise, the drum always taking the shorter position to bring the next selected compartment to a check receiving position. Hence, the printer frames 102, 103 at the right and left sides of the machine will follow such clockwise or counterclockwise movement of the sorting drum but it is obvious that the relationship shown in the chart of Fig. 3 will be maintained in selecting compartments according to the presently adopted principle of operation. Whether the sorting drum rotates backwardly or forwardly, the selection of compartments 1 to 12 will cause the printing wheels 109 at the right side of the machine to always print upon the tapes surrounding the related platens 1-12 and the same statement can be made for the selection of the printing platens 13-24 at the left side of the machine when the compartments 13 to 24 are selected for check reception.

Aligning mechanism for printer frames

When the printer frames are adjusted to their predetermined radial positions it is desirable that they be aligned in such positions and to this end an aligning mechanism is provided which is shown in Fig. 6.

As shown in the drawings for the printer at the right side of the machine, each of the printer side frame plates 102-103 is provided with a depending segment 130 provided at the periphery with aligning notches 131, there being one aligning notch for each radial position of the printer frame. In the radial position of a printer frame a selected notch 131 of both plates 102, 103 is engaged by an aligning bail 132. This aligning bail is of the customary form consisting of two side arms and the cross bail member 132 and the bail is loosely pivoted on a support shaft 133. One side arm of the bail has an extension which has a link connection 134 to an arm 135 loosely pivoted on a support shaft 136. An arm 137 integral with the arm 135 has a link connection 138 to an arm 139 attached to the rock shaft 75. The means for rocking the shaft so as to operate the aligning mechanism for the actuating segments 71 has previously been described and obviously when the shaft 75 is rocked to effect this aligning function, arm 139 will also be rocked clockwise, link 138 will be moved downwardly and through the rocking of the arm 137 and the link 134 bail 132 will be moved upwardly to aligning position. The cross member of this bail will engage the aligning notches 131 for both printer side frame plates 102, 103, thus aligning them in the radial position of the printer frame.

13

Fig. 6 shows the aligning bail mechanism for the printer at the right side of the machine but for the left side of the machine the shaft 136 is transversely extended and by similar connections from this shaft the aligning bail 132 for the left printer side frame is concomitantly positioned.

Printing mechanism

After the two groups of printing wheels 109 have been differentially rotated, an impression is then taken from the group of wheels coordinated with a selected platen. The impression operation is effected after the segments 65 have been differentially adjusted and after the printer frames are aligned by the aligning mechanism shown in Fig. 6. The means for effecting the printing impression is performed by a plate 150 known as an "operating plate," there being one of such plates for each of the two printers. The plate 150 is loosely pivoted on the shaft 101 (see Fig. 4), and receives a commensurate movement with the related printer frame and in any radial position of the printer frame the operating plate 150 is reciprocated to effect the impression operation as well as to cause the paper tape feed. The operating mechanism for reciprocating plate 150 is shown in Fig. 7. The main drive shaft 94 drives a box cam 151, the cam race of which cooperates with a follower arm 152 which, through a double arm 153, shifts a link 154, said link being connected to the midpoint of an arm 155 loosely mounted upon a rod 156. The upper end of arm 155 has a bifurcation receiving a stud of an arm 157 secured to a rock shaft 158. At substantially the midpoint in the operation of the machine cam 151 will rock arm 152 clockwise, rocking the double arm 153 counterclockwise and pulling link 154 to the left as shown in Fig. 7, resulting in the rocking of shaft 158 clockwise. Thereafter, a reverse operation ensues so as to rock the shaft 158 counterclockwise. For each printer there are similar operating connections from shaft 158 to reciprocate the related operating plate 150 and identical to that shown in Fig. 7.

To the rock shaft 158 there is secured an arm 159 having a link connection 160 to a bell crank 161 on which is pivotally mounted an operating pawl 162. A spring 163 extending between an extension of the bell crank 161 and the pawl 162 urges the operating pawl 162 to engage an operating notch 164 of the operating plate 150 but such action is normally prevented by the contact of a pin 165 carried by pawl 162 with the underside of one of the arms that carry the bail 132 (Fig. 8). It is evident that when the bail 132 is lowered by the operating mechanism to align the printer frame, spring 163 will be effective to rock the pawl 162 so that its operating extension will fit into one of the notches 164 of the operating plate 150.

In this manner the pawls 162 for the two printers will move upwardly towards notches 164 of plates 150 but since one of the printer frames at has a midway position it is clear that its operating pawl 162 will not engage a notch 164 but will instead contact the periphery of the operating plate 150 between adjacent notches 164. Hence, the first action of cam 151 will cause, after the positioning of pawl 162 in a notch 164 of one plate 150 the movement of the pawl 162 to the right as shown in Fig. 7 to rock the operating plate 150 for one printer frame. However, the rocking of the pawl 162 for the other printer is not sufficient to enable pawl 162 to engage any

of the projections 164 and hence the related operating plate 150 will not be actuated. The reverse operation of the linkage shown in Fig. 7 and operated by the cam 151 will then cause pawl 162 to be moved to the left resulting in a reverse rocking of the operating plate. This reciprocation of the plate 150 will operate mechanism now to be described to effect the printing impression.

It is evident from Fig. 8 that the aligning plate 130 has twice as many notches 131 as the notches 164 of operating plate 150 so that even each midway position of a printer frame will be aligned, but in the midway position of such printer frame there will be no reciprocation of the operating plate 150 because there is only one notch 164 for each printing position of the printer frame.

In this manner a printing impression is taken only from the group of printing wheels which are coordinated with a platen, eliminating useless printing operations from the group of wheels of the printer which is not selected for operation.

To enable the group of printing wheels of each of the printers to be impressed against the selected platen 99, said printing wheels are carried by an independent frame which is journaled in the related printer frame 102-103 by the following construction.

This frame consists of a side frame plate 166 and a parallel side frame plate 167 (Figs. 4 and 9) which are joined transversely by a cross piece 168 to provide a rigid supporting frame. Extending laterally from the side frame plates 166 and 167 are journal pins 169 (Fig. 4) each of which extends into the related printer side frame 102-103 so that the printing wheel carrying frame 166-167 may be rocked about such journal pins. The printing wheel carrying frame 166, 167 also carries a rod 170 and on this rod are mounted the printing wheels 109 and the pinions 108. When the printing wheel support frame is in the position shown in Fig. 4 and Fig. 11, it is clear that the pinions 108 are in mesh with their actuating pinions 107.

Fixed to the support rod 170 for the group of printing wheels 109 is a plate 171 (Fig. 11) and said plate is apertured so that one of the journal pins 169 of the printing wheel carrying frame passes through such aperture. The plate 171 is mounted outside of the side frame plate 167 and by the connection just described it is evident that it partakes of any swinging movement of the printing wheel carrying frame about the journal pins 169. Extending from the plate 171 is a link 172 to which a normally tensioned spring 173 is secured. The normal tension in the spring 173 therefore attempts to rock the printing wheel carrying frame clockwise about the journal pins 169 but such action is normally prevented by the abutment of an extension 174 of the plate 171 with an extension 175 of the now stationary operating plate 150. It has been stated that operating plate 150 assumes the same radial positions as the printer frame and this is effected by the following connection.

The side plate 103 as shown in Fig. 9 and Fig. 11 carries a stud 176 passing through a hub 176a carried by a printing wheel release plate 177. One end of the spring 173 is secured to said release plate. The release plate 177 carries a roller 178 fitting in the bottom portion of a notch 179 of the operating plate 150 and with the operating plate 150 in any position it is evident that the tension in the spring 173 attempts to rock the release lever 177 about its pivotal point 176 and such action is normally

prevented by cooperation of the roller 178 in the bottom portion of the notch 179 in the operating plate 150. The tension on the spring 173 and the cooperation of the projection 174 with the extension 175 of the operating plate 150 maintains the printing wheel carrying frame in such position that pinions 108 are maintained in mesh with the actuating pinions 107 and spring 173 is ineffective to rock the printing wheel carrying frame to impress the printing wheels 109 against a selected platen 99. However, the printing wheel carrying frame is released or unlatched to effect this printing impression by means to be described.

By the aforesaid rocking movement of the operating plate 150 effected by means previously described the operating plate 150 is first rocked counterclockwise as viewed in Fig. 11, bringing the extension 175 away from the extension 174 and since this cooperation normally restrains the rocking of the printing wheel carrying frame by the normally tensioned spring 173, such frame would be released for a rocking movement at this time but such action is prevented by cooperation of the extension 174 with a latch pawl 205 pivoted on the plate 103. As the operating plate 150 rocks counterclockwise the cooperation of the lower part of notch 179 in the plate 150 with the roller 178 carried by the release lever 177 causes roller 178 to be moved concentrically about the pivot point 176 of the release lever 177. This results in the rocking of the release lever 177 in a clockwise direction about its pivot stud 176 so that at a certain point in this rocking movement a projection 206 of the release lever 177 will hit a stud 207 of the latch pawl 205, rocking the latter so as to disengage it from the extension 174. During the rocking of the release lever 177, spring 173 is further extended and tensioned and at the time it is sufficiently extended the latch pawl 205 is completely disengaged from the latch extension 174 and the spring 173 is effective to rock the printing wheel carrying frame about the journal pins 169 to impress the group of printing wheels against the selected platen with a hammer blow.

In any customary manner an inking ribbon 203 (Fig. 4) may be interposed between the group of printing wheels 109 and the paper tapes so that in any position of the printer carrying frame the printing impression will be effected on the selected paper tape.

In the reverse rocking movement of the operating plate 150 which is clockwise as viewed in Fig. 11, the extension 175 will engage the extension 174 and rock the printing wheel carrying frame about its journal pins 169 until the parts are in the normal position shown in Figs. 4 and 11. By reverse action the print release lever 177 will also be brought back to its normal position.

Hence, in any radially adjusted position of either printer frame the common operating means of the machine will effect the unlatching of the group of printing wheels to be selected for a printing impression to cause the selected group of printing wheels to be impressed against the platen.

Aligning mechanism for printing wheels

It is desirable that the group of printing wheels 109 be aligned and firmly held to secure a straight line of print on the paper tape because when moved to effect the printing impression the related gears 108 are out of mesh with the actuating gears 107 and therefore are not restrained or locked. To this end, there is provided an

aligning bail 210 pivoted between frame plates 166, 167 and having aligning fingers 211 (Figs. 4 and 9) which aligning fingers are adapted to fit within the interdental spaces of the pinions 108. The aligning fingers 211 are normally out of engagement with pinions 108 because in the normal position of the print release lever 177 a lateral extension or lug 212 (Fig. 12) thereof is in contact with a pin 213 extending from the bail 210. This retains the bail in such position that fingers 211 do not engage pinions 108.

However, when the print release lever 177 is rocked clockwise the lug 212 will be shifted away from the pin 213 and a spring 214 (Fig. 4) will now rock the bail about its pivot pins 215 on the printing wheel carrying frame 166, 167 and aligning fingers 211 will now lock pinions 108 and the printing wheels 109. Of course, when the print release lever 177 is restored, reverse action will take place and bail 210 will be brought to the normal position shown in Fig. 12, enabling the free rotation of the printing wheels 109.

The print release lever 177 is provided with a cam slot 216 (Fig. 13) cooperating with a roller 217 carried by a reciprocable arm 218 pivoted at 219 on the printer side frame plate 103. The cam formation 216 is such that the rocking of the print release lever 177 clockwise will rock the arm 218 downwardly and then by the restoration of the print release lever the arm 218 will be returned upwardly to normal position. As will be subsequently described, the reciprocation of arm 218 will effect the paper feed operation.

Paper tape carrying devices for the printing mechanisms and paper tape feeding devices

For each side of the machine there are twelve identical printing mechanisms each of which includes means for carrying and feeding the record tapes against which the printing wheels 109 are impressed. The arrangement of the printing mechanisms for the right side of the machine is shown in Figs. 8 and 9 and the specific construction of each will now be given.

Each printing mechanism consists of the casting 98 which carries the individual platen 99. Pivoted upon a stud 180 (Figs. 8 and 9) carried by the side frame plate 95 is an arm 181 and said arm carries a spindle 182 on which is placed a supply roll of paper 183. The paper tape 100 leads off the roll 183 and extends downwardly as indicated by 184 (Fig. 8), thence passing around the platen 99, upwardly from the platen as indicated by 185, thence around a feeding roller 186 and is then guided by a guide plate 187. As the paper tape is fed upwardly or outwardly it drops by gravity over a circular plate 188 (Fig. 1). It is pointed out that all of the paper tapes for the twelve printing mechanisms emerge in this manner exteriorly of machine over the circular plate 188 and as they are printed and fed in increments they drop over the plate 188 in an overlapping manner to be detached by the operator at will.

It is, of course, necessary to feed the paper tape an increment after each printing operation and to this end the paper supply roller 183 is spring-urged so that the paper tape at 185 is between the feeding roller 186 and the periphery of the supply roll 183. By rotating the roller 186 in increment it is obvious that it shifts or feeds the paper a step and at the same time rotates the supply roll 183 clockwise to unwind the paper tape. For the above described frictional engagement, surrounding the stud 180 is a coil spring

190 (Figs. 8 and 9), one end of which bears against a fixed stud 191 and the other against the spindle 182. With the arrangement of the spring shown in Fig. 8 it is obvious that the desired frictional relationship is secured.

To provide the step by step increment of the feeding roller 186 the latter has secured thereto a ratchet wheel 192 (Fig. 9) which is engaged by the operating end 193 of a reciprocating plate 194. A spring 195 urges the operating end of the plate 194 against the ratchet wheel 192 and the plate 194 is slotted at 196 to be received by the lower stud 97. (See Fig. 13.) Each plate 194 carries a stud 198. Obviously, by depressing each plate 192 its operative relationship with the ratchet 192 of the feeding roller 186 of the related printing mechanism will feed the paper tape of that printing mechanism a step to space the printed items. Obviously, since the only paper tape of the platen which is selected for operation should be operated, means is provided to selectively operate each of the plates 192. To this end the reciprocating arm 218 is provided with lateral lugs 199. (Fig. 13.) In accordance with the radial position of the printer frame the lugs 199 will be underneath and over the stud 193 of the plate 194 of the selected platen and when said arm 218 is rocked the upper lug 199 will contact the stud 193 and depress the plate 194 to feed the paper strip. The arm 218 is rocked prior to the snapping of the printing wheels 189 against the platen 99 and therefore the paper tape of the selected platen is fed to bring the last printed line away from the platen 99 and present a fresh portion of the paper tape to the platen 99.

If so desired the guide plate 187 (Fig. 8) of each printing mechanism may be equipped at its outer end with a serrated edge whereby the operator may detach the printed portion of the paper tape from the remainder. The construction is such that it is possible for the operator to pull outwardly on the printed and projecting part of the tape to unroll it from the supply roller sufficiently so that the last printed item is away from the severing point at which it is detached. To facilitate such feeding operations each spindle 186 carries a knurled knob 200 (Fig. 9) which is accessible to the operator and can be rotated to feed the paper tape the desired amount independently of the operation of the machine.

Exhausted compartment tape signal

The present machine also includes the arrangement fully shown and described in the patent to F. L. Fuller, et al., No. 2,142,352 by which the machine is locked up and the operator receives a signal when any of the rolls of paper are exhausted. The present construction is somewhat different from the patented construction and will now be described.

The paper rolls 183 are individually carried by the arms 181 and each is provided with an extension 225 (Fig. 8) in the plane of a related stud 226. The studs 226 are carried by an arcuate portion 227 of a frame which consists of the arcuate portion 227 and radial arms 228 and 229, which frame is pivoted upon a stud axially with respect to the shaft 101. Obviously, as the diameter of each paper roll reduces, the arm 225 will approach the stud 226 and the reduction in the size of the roll which occurs when the last of the paper strip has been drawn from the roll causes the counterclockwise rocking of the aforementioned segment frame. It will be observed that this frame also carries an extra pin or stud 230

(Fig. 8) which, when the frame is rocked counterclockwise, will close contacts 231. The closure of such contacts closes circuits to light a signal light and also to lock up the machine. Of course, both sides of the machine are provided with the same sort of signal control so that in case any one of the twenty-four paper rolls 183 is completely unwound, the operator will be accordingly signalled so that a new paper supply can be inserted in the machine.

Ribbon feed and associated feeding mechanism

It has been indicated that the machine is provided with a wide ribbon strip designated by reference numeral 238 and such ribbon passes beneath all of the twelve platens 99 for each side of the machine. Any suitable ribbon reversing mechanism may be provided so that the ribbon is fed in one direction and then to the other to continuously present a fresh supply of inked ribbon to the printing wheels and platens. No description is given herein of the presently used ribbon feeding mechanism since it is conventional in structure and operation.

Means for indicating and printing a designation indicating compartment at check receiving position

As in Patent No. 2,142,352 the present machine also includes an arrangement which sets up printing elements indicating the particular compartment in which a check is sorted and to also set a visible indicator which the operator may look at to check the compartment selected before he depresses the motor release bar 47 to cycle the machine. The present construction is somewhat different from that shown in the machine of Patent No. 2,142,352 and is shown in Fig. 10.

Rotatable with the pinion 129 is a larger pinion 235 which is in mesh with a slidably mounted rack 236 and the latter has an integral rack slide 237 meshing with a gear 238 secured to an indicating wheel 239. This, as in the patented machine, is provided in the front of the machine (see Fig. 1) so that characters on the wheel will indicate the position that the sorting drum is in. A supplemental rack portion 240 of the slide 237 meshes with a pinion 242 secured to a shaft 241. The shaft 241 also carries another pinion like the pinion 242 which meshes with the rack teeth 243 of a type bar 244. This type bar will print upon the control tape a numeral indicating which compartment has been selected for check sorting operations. The sorting drum remains in the last selected position and is rotated in either direction to bring the next selected compartment to position. Consequently, the type bar 244 may be moved upwardly and downwardly and the indicator 239 may be rotated clockwise or counterclockwise, bringing both to such numeral designating positions that a character will be printed and indicated that corresponds to the position of the sorting drum.

Means for indicating the taking of a total and designating compartment tape number upon printing a total on each compartment tape

The machine in which the present improvements are incorporated is provided with means for not only printing the amounts on each compartment tape corresponding to the records sorted in the related compartment but to also print the total of such amounts on the strip or tape. Reference may be had to the aforementioned patents for the operation of the total taking mechanism, it being observed that this is initiated by the

depression of a total taking key. The operation of this key arranges to set a character to print T alongside of the total amount and to also print the number of the compartment when the total is taken. This compartment number on the tape identifies the classification of the amounts and the related totals.

By any suitable means, depression of the total key may be arranged to shift a link 260 (Fig. 4) which, through an arm 261, rocks a shaft 56T. 10 This shaft as observed in Fig. 4 is the top shaft of the series and by connections previously described in connection with the setting up of the segments 65 for each printer, two additional segments 65N and 65T (Fig. 9) are adjusted to the 15 position of a single step. The segment 65T will, through pinions 106, 107 and 108, turn the wheel 109T a step to bring the printing character T to printing position. This character will be printed on the record tape selected for printing of the 20 total of the amounts of checks sorted in the related compartment.

The segment 65N will, through similar pinions 106, 107 and 108, turn or adjust a disk 262 which is loosely mounted on the shaft 170. This disk is provided with a lug 263 (Fig. 9) which, in the adjusted position of the disk 262, will be beneath a printing type 264 (Fig. 4) which is carried by a spring plate 265. Hence, when the group of printing wheels 109 is unlatched and strikes the platen 99 with a hammer blow, the lug 263 will strike the type 264 to print the related compartment number on the control tape. This provides for not only printing the total on a line but also the number of the compartment and the designation "T," meaning that the amount printed is a total of the items printed on the tape.

While there have been shown and described and pointed out the fundamental novel features of the invention as applied to a single modification, it will be understood that various omissions and substitutions and changes in the form and details of the device illustrated and in its operation may be made by those skilled in the art without departing from the spirit of the invention. It is the intention therefore to be limited only as indicated by the scope of the following claims.

What is claimed is:

1. In a printing machine, two sets of printing wheels, separate movable frames each carrying one of the sets of printing wheels, said movable frames being connected together so as to cause said frames to have such relative positions that one set of printing wheels has a normal printing position in a series of printing positions when the other set has a position one-half step away from the normal printing position in another series of printing positions, and reciprocating means for said frames to simultaneously move both of said frames in either direction to position one set of printing wheels at a series of printing positions as the other set is maintained a one-half step away from its series of printing positions, and said last named means including means operable at the termination of the full extent of movement in either direction to reverse the direction of movement of said frames and to cause a concurrent one-half step of movement of both frames to now move the set of wheels previously one-half step away from a printing position to printing position, and to now move the other set of wheels previously at printing position to a position one-half step away from printing position.

2. In a printing machine, two sets of printing wheels, each carried by a separate movable frame,

means connecting each of said movable frames to cause said frames to have such relative positions that one set of printing wheels has a normal printing position in a series of printing positions when the other set has a position one-half step away from the normal printing position in another series of printing positions, reciprocating means for said frames including cam means to simultaneously move both of said frames in either direction to position one set of printing wheels at a series of printing positions as the other set is maintained a one-half step away from each of its series of printing positions, and said cam means including means operable at the full extent of movement of the frames in either direction to reverse the direction of movement of both frames and to cause a concurrent one-half step of movement of both frames to move a set of wheels previously one-half step away from a printing position to printing position and to move the other set of wheels previously at printing position to a position one-half step away from printing position.

3. In a printing machine, two sets of printing wheels, each carried by a separate movable frame, means connecting each of said movable frames to cause said frames to have such relative positions that one set of printing wheels always has a normal printing position in a series of printing positions when the other set has a position one-half step away from the normal position in another series of printing positions, reciprocating means for said frames including rotatable cam means to simultaneously move both of said frames in either direction and for successive equal angular movements of said cam means to position one of the sets of printing wheels at a series of printing positions as the other set is maintained a one-half step away from each of its series of printing positions, and said cam means including diametrically opposite means operable at the full extent of movement of the frames in either direction to reverse the direction of movement of said frames and to cause a concurrent one-half step of movement of both frames to move a set of wheels previously one-half step away from a printing position to printing position, and to move the other set of wheels previously at printing position to a position one-half step away from printing position.

4. In a printing machine, two sets of printing wheels, each carried by a separate movable frame, means connecting each of said movable frames to cause said frames to have such relative positions that one set of printing wheels always has a normal printing position in a series of printing positions when the other set has a position one-half step away from the normal printing position in another series of printing positions, reciprocating means for said frames including cam means operable through 360° to simultaneously move both of said frames in either direction for successive equal angular movements of the cam means to position one of the sets of printing wheels at a series of printing positions as the other set is maintained at one-half step away from each of its series of printing positions, and said cam means including diametrically opposite cam means operable at the full extent of movement of said frames in either direction to cause the direction of movement of said frames to be reversed and to cause a concurrent one-half step of movement of both frames to move a set of wheels previously one-half step away from a printing position to printing position, and

to move the other set of wheels previously at printing position to a position one-half step away from printing position.

5. In a printing machine, two sets of printing wheels, each set carried by a related movable frame, two series of platens, one series for each set of printing wheels, means connecting said movable frames to cause said frames to have such relative positions that one set of printing wheels is always coordinated with a platen of one series when the other set of printing wheels occupies a position a one-half step away from a platen of the other series, and means for simultaneously moving said frames in either direction to cause the first of said sets of printing wheels to be successively coordinated with the related series of platens as the other or second set of printing wheels maintains its one-half step position away from the related series of platens, and including means operable at the full extent of movement in either direction to then reverse the direction of movement of said frames and to cause concurrently a one-half step movement of both of said frames to coordinate the second set of printing wheels with one of the related series of platens as the first of said sets of printing wheels is moved to occupy a one-half step position away from one of the related series of platens.

6. In a printing machine, two sets of printing wheels, each set carried by a related movable frame, two series of platens, one for each set of printing wheels, means connecting said movable frames to cause said frames to have such relative positions that one set of printing wheels is always coordinated with a platen of the related series when the other set of printing wheels occupies a position one-half step away from a platen of the other series, and reciprocating means including cam means for moving the connecting means to simultaneously move said frames in either direction to cause the first of said sets of printing wheels to be successively coordinated with the related series of platens as the other or second set of printing wheels maintains its one-half step position away from the related series of platens, and including means operable at the full extent of movement in either direction to reverse the direction of the movement of said connecting means and said frames and concurrently effecting a one-half step movement of both of said frames to coordinate the second set of printing wheels with one of the related series of platens as the first of said sets of printing wheels is moved to occupy a one-half step position away from one of the related series of platens.

7. In a printing machine, two sets of printing wheels, each set carried by a related movable frame, two series of platens, one for each set of printing wheels, means connecting said movable frames to cause said frames to have such relative positions that one set of printing wheels is always coordinated with a platen of one series as the other set of printing wheels occupies a position one-half step away from a platen of the other series and means for simultaneously moving said frames in either direction to cause one of said sets of printing wheels in either direction of movement to be successively coordinated with the related series of platens as the other set of printing wheels maintains its one-half step position away from the related series of platens, and including means operable as the full extent of movement of said frames in either direction is completed to reverse the direction of movement of said frames and to cause an initial one-half step

movement of both of said frames to coordinate one set of printing wheels with one of the related series of platens as the other of said sets of printing wheels is moved to occupy a one-half step position away from one of the related series of platens.

8. In a printing machine, two sets of printing wheels, each set carried by a related movable frame, two series of platens, one for each set of printing wheels, means connecting said movable frames to cause said frames to have such relative positions that one set of printing wheels is always coordinated with a platen of the related series as the other set of printing wheels occupies a one-half step position away from a platen of the other related series, and reciprocating means for said frames including cam means for simultaneously moving the connecting means to move both of said frames in either direction to cause for successive equal angular movements of said cam means the first of said sets of printing wheels to be moved to be successively coordinated with the related series of platens as the other or second set of printing wheels maintains its one-half step position away from the related series of platens, said cam means provided with means operable as the full extent of movement of said frames in either direction is completed for reversely moving both of said frames one-half step to coordinate one set of printing wheels with one of the related series of platens as the other of said sets of printing wheels occupies a one-half step position away from one of the related series of platens.

9. In a printing machine, having two sets of printing wheels, a movable frame for each set of printing wheels, means for connecting said frames so that they normally have such relative positions that one set of printing wheels is always at a normal printing position as the other set of printing wheels is a one-half step away from a printing position, a set of differentially actuated racks for each set of wheels, means for concurrently setting both of said sets of racks to differential positions while both of said frames and wheels are at rest, to thereby set said wheels to represent a value to be printed from one of said sets of wheels, means for moving said frames in one direction while said differentially actuated racks are at rest to cause one of the sets of printing wheels to occupy successive printing positions as the other set occupies successive positions one-half step away from printing position and for then reversing the direction of movement of the frames and concurrently causing the printing wheels which were one-half step away from printing position to now occupy a printing position as the printing wheels previously at printing position are now positioned one-half step away from printing position, and means for positioning said wheels and the related sets of racks so that as each set of wheels is moved from one printing position to an adjacent printing position the printing wheels will roll over the now stationary racks to maintain the value representing positions of the wheels effected by the differential actuation of the racks.

10. In a machine having the structure defined in the preceding claim 9 in which each set of printing wheels has a coordinated series of platens, and means to position each series of platens so that at printing position one of the sets of wheels may effect a printing impression therefrom while the other set of printing wheels which is positioned one-half step away from a platen

of the related series is incapable of effecting a printing impression.

11. In a printing machine, having two sets of printing wheels, a series of platens for each set of printing wheels, a movable frame for each set of printing wheels, means for connecting said frames so that they have such relative positions that one set of printing wheels is at a printing position with respect to a platen of the related series as the other set of printing wheels is a one-half step away from a platen of its related series, a set of differentially actuated racks for each set of wheels, means for concurrently setting both of said sets of racks to differential positions while both of said frames and wheels are at rest, to thereby set both of said sets of wheels to represent a value to be printed from one of said sets of wheels, means for moving said frames in reverse directions while said differentially actuated racks are at rest to cause one of the sets of printing wheels to occupy successive printing positions as the other set occupies successive positions one-half step away from a platen and for reversing the direction of movement of the frames and concurrently causing the printing wheels which were one-half step away from printing position to be now coordinated with its related series of platens as the printing wheels previously at printing position are now positioned one-half step away from a platen, means for positioning said wheels and the related sets of racks so that as each set of wheels is moved from one printing position to an adjacent printing position the printing wheels will roll over the now stationary racks to maintain the value representing positions of the wheels previously effected by the differential actuation of the racks, and means for effecting a printing movement of the set of printing wheels which are coordinated with a platen to print the value on a record strip passing around said platen.

12. A printing machine comprising a set of printing wheels, an angularly positioned frame carrying said set of printing wheels, a series of platens adapted to be successively coordinated with said printing wheels, means for effecting a printing relationship of the printing wheels and a single platen which is selected for operation by the extent of angular positioning of said frame, an operating member carried by said frame and movable therewith and actuated independently of said frame to cause the operation of said last

named means, and means for actuating said member in any angular position of said frame.

13. In a machine of the class described, the combination of two sets of wheels, two series of platens, one series for each set of wheels, related frames carrying said wheels, means for effecting a relative disposition of said frames to cause one set to be at a position midway of printing positions when the other set is coordinated with a platen, two sets of racks for rotating said sets of wheels, means for differentially positioning said racks to rotate said sets of wheels to value representing positions, means for moving said frames in reverse directions and for causing in one direction the coordination of only one set of wheels with the related platens and in the other direction the coordination of only the other set of wheels with the related platens, the movement of said frames causing the wheels to be rolled in one direction or the other over the related set of racks dependent upon the direction of movement of the frames but maintaining the value representing position of said wheels effected by the differential positioning of said racks, and means to effect a movement of the set of wheels at printing position against the platen of the series coordinated therewith and which was selected by the extent of movement given to said frames by said moving means.

14. In a machine of the class described, two sets of printing wheels, each set movable in equal steps to successive printing positions, means for effecting relative positions of one-half step apart of said sets of wheels whereby one set is at a printing position as the other set is at a one-half step away from printing position, and means for bodily moving the two sets of wheels in reverse directions to cause in one direction of movement only one set of wheels to move to successive printing positions as the other set of wheels occupies positions midway of printing positions and then cause a reverse direction of movement of said sets of wheels and concurrently effect an alternate positioning of said sets of wheels, whereby only the set of wheels previously occupying positions midway of printing positions now has successive printing positions.
